CLAIM

The ornamental design for a container plug, as shown and described.

DESCRIPTION

FIG. 1 is a top perspective view of a container plug, showing a first embodiment of my new design;

FIG. 2 is a bottom perspective view of FIG. 1;

FIG. 3 is a front elevational view of FIG. 1;

FIG. 4 is a rear elevational view of FIG. 1;

FIG. 5 is a left-side elevational view of FIG. 1, the right-side elevational view being a mirror image thereof;

FIG. 6 is a top plan view of FIG. 1;

FIG. 7 is a bottom plan view of FIG. 1;

FIG. 8 is a cross-sectional view thereof, taken along line 8-8 of FIG. 3;

FIG. 9 is a top perspective view of a second embodiment thereof;

FIG. 10 is a bottom perspective view of FIG. 9;

FIG. 11 is a front elevational view of FIG. 9;

FIG. 12 is a rear elevational view of FIG. 9;

FIG. 13 is a left-side elevational view of FIG. 9, the right-side elevational view being a mirror image thereof;

FIG. 14 is a top plan view of FIG. 9;

FIG. 15 is a bottom plan view of FIG. 9;

FIG. 16 is a cross-sectional view thereof, taken along line 16-16 of FIG. 11;

FIG. 17 is a top perspective view of a third embodiment thereof;

FIG. 18 is a bottom perspective view of FIG. 17;

FIG. 19 is a front elevational view of FIG. 17;

FIG. 20 is a rear elevational view of FIG. 17;

FIG. 21 is a left-side elevational view of FIG. 17, the right-side elevational view being a mirror image thereof;

FIG. 22 is a top plan view of FIG. 17;

FIG. 23 is a bottom plan view of FIG. 17; and,

FIG. 24 is a cross-sectional view thereof, taken along line 24-24 of FIG. 19.

The broken lines in the figures depict portions of the container plug that form no part of the claimed design.
